[57] ABSTRACT

Several embodiments of a high power wideband balun transformer are disclosed. In each embodiment a single high permeability magnetic core is incorporated. It is wound with a balun winding which converts an unbalanced impedance Z_u at unbalanced terminals to an equal balanced impedance across a gap region. Balanced terminals are connected to the gap region of the balun winding by impedance transforming means, so as to provide a balanced impedance Z_b which is not equal to the unbalanced impedance Z_u . When the impedance transforming means are the outer conductors of the balun winding a selected number of turns from the gap region, Z_b is less than Z_u . When the impedance transforming means are additional windings wound about the core Z_b is greater than Z_u , and the ratio Z_b/Z_u is a function of the number of turns N_b between the balanced terminals and the number of turns N_p of the balun winding. Apertures insulating boards are employed to control the spacings between the windings and the core, and the spacings between adjacent turns of the balun winding and the impedance transforming winding.

BALUN TRANSFORMER WITH A SINGLE MAGNETIC CORE AND IMPEDANCE TRANSFORMING MEANS

BACKGROUND OF THE INVENTION

1. Field of the Invention

The present invention generally relates to balun transformers and, more particularly, to an improved balun transformer of the type in which windings are wound on a single magnetic core and which is capable of high power and/or wideband operation.

2. Description of the Prior Art

As is known a balun transformer, or simply a balun, is a device which transforms an unbalanced impedance with respect to ground to a balanced impedance. Some baluns are of the non-impedance transforming type in that they transform an unbalanced impedance only to an equal balanced impedance, while other type baluns transform the unbalanced impedance to a different balanced impedance. The latter type may be referred to as an impedance transforming balun.

In the prior art the bandwidth of operation of baluns has been extended by winding the balun winding on a high permeability magnetic core. One example of such a prior art balun is shown in "Antenna Engineering" by Walter L. Weeks, page 173, published by McGraw-Hill Book Company, Library of Congress Catalog Card Number 68-13106. The single core balun described therein is of the nonimpedance transforming type. An impedance transforming balun is also described in the same book. However the latter requires two cores and is capable of only a 4:1 impedance transformation ratio.

C. L. Ruthroff, in an article entitled "Some Broadband Transformers" appearing in Proceedings of the IRE, Vol. 47, Part 2, pages 1337-1342, published August 1959, discloses several impedance-transforming and non-impedance transforming baluns which are wound on a single high permeability magnetic core. The baluns disclosed by Ruthroff have satisfactory electrical balance characteristics only when the length of their windings, as measured in wavelengths, is very small. Therefore, they are not suitable for high power applications which necessitate cores with large cross sections, and hence windings of appreciable length. Also, the low power version baluns, described by Ruthroff, have bandwidths which are unnecessarily limited for many applications. Thus, a need exists for a new broadband balun of the impedance transforming type. Furthermore a need exists for a high power broadband impedance transforming type balun which is not limited by limitations, characterizing prior art baluns.

OBJECTS AND SUMMARY OF THE INVENTION

It is a primary object of the present invention to provide a new broadband impedance transforming balun.

Another object of the invention is to provide a new single core balun with a wide range of unbalance to balance impedance ratio.

A further object of the invention is to provide a novel high power broadband impedance transforming balun.

These and other objects of the invention are achieved by providing a single high permeability magnetic core on which are wound both the balun and the impedance transforming windings. The latter are con-

nected to the balun windings and wound to provide the desired unbalance to balance impedance ratio, hereafter referred to as the impedance transformation ratio. Broadband capability at high power is achieved by proper spacing of the impedance transforming windings with respect to the balun windings, as will be described hereafter in detail.

The novel features of the invention are set forth with particularity in the appended claims. The invention will best be understood from the following description when read in conjunction with the accompanying drawings.

BRIEF DESCRIPTION OF THE DRAWINGS

FIG. 1 is a top view of one embodiment of the invention;

FIG. 2 is a cross-sectional view of a basic embodiment of the invention with insulating boards;

FIG. 3 is a top view of another embodiment of the invention;

FIG. 4 is a simple diagram useful in explaining one of the embodiments of the invention;

FIG. 5 is a view of another embodiment; and

FIGS. 6 and 7 are top and side views respectively of yet another embodiment of the invention.

DESCRIPTION OF THE PREFERRED EMBODIMENTS

Attention is first directed to FIG. 1 which is a diagram of one embodiment of a balun in accordance with the present invention in which an unbalanced impedance Z_u is transformed into a balanced impedance Z_B which is smaller than Z_u . The balun winding is formed of a coaxial transmission line 11 of a characteristic impedance Z_u which makes a plurality of turns, defined N_p , through the center of a magnetic core 12. In the particular example $N_p=6$.

Both ends of the outer conductor or shield 14 of the coaxial line 11 are conductively joined together and connected to ground, which represents one unbalanced terminal. The other unbalanced terminal, designated by numeral 15, is connected to the inner conductor 16 of the coaxial line 11 at one end thereof. The unbalanced impedance Z_u is between terminal 15 and ground.

As seen from FIG. 1, the coaxial line 11 is completely severed at its midpoint to form a gap 18 and the center conductor 16 is either removed from one half, such as the left half of the line, or is shorted to the outer conductor of that half at gap 18. The center conductor 16 in the right half of the line is joined across the gap to the shield 14 of the left hand half of the line 11. The balun winding is spaced some distance away from the magnetic core 12 to minimize both dielectric and magnetic core losses. The spacings may best be controlled by placing two electrically insulating boards 20 and 21 on opposite sides of the core, as shown in FIG. 2, and passing the winding through holes or apertures 22 in the boards.

As should be appreciated by those familiar with the art the impedance across the gap 18 is balanced and is equal to Z_u . In accordance with the present invention however, the balanced terminals, designated in FIG. 1 by numerals 25 and 26 are not connected across the gap. Rather, they are connected to the shield or outer

conductor 14 of the balun winding at points which are a given number of turns from ground. In the particular example each of terminals 25 and 26 is connected to the shield two turns from ground.

In this particular embodiment the shield 14 of line 11 is in effect being used as a balanced autotransformer. As long as the balun winding, formed by the shield 14, is short in terms of a wavelength, the balanced impedance, defined as Z_B , across terminals 25 and 26 is related to the balanced impedance at the gap defined as Z_G , which equals Z_U by the relationship

$$Z_B = Z_G (N_s/N_p)^2 = Z_U (N_s/N_p)^2 \quad (1)$$

In the above expression $N_s/2$ is the number of turns between each balanced terminal and ground, and $N_p/2$ is the number of turns between the gap and ground. In the present example $N_s=4$ and $N_p=6$. Thus,

$$Z_B = Z_U (4/6)^2 = 4/9 Z_U \quad (2)$$

As is appreciated the unbalanced current which flows in the center conductor 16 and the inside of the outer conductor or shield 14 and which is designated I_u divides into a balanced current I_b and a remainder current I_m which flows on the outside of the shield 14 of the right and left halves of the balun winding 11. The symmetry of the balun winding, formed by the outside of the shield 14, insures that the balanced terminals of the balun are electrically balanced with respect to ground at all frequencies. The range of frequencies over which Z_B is essentially equal to $4/9 Z_G$ is determined by the range of frequencies over which the current I_m is small with respect to I_b . Actually,

$$I_b/I_m = Z_M/Z_B \quad (3)$$

where Z_M is the magnitude of the impedance of the inductance formed by the total number of turns N_p of the outer shield 14 of the balun winding 11. In FIG. 1 $N_p=6$.

At low frequencies where the length of the winding is small in terms of wavelength, the impedance of the winding is inductive and the magnitude of the impedance is directly proportional to the product of frequency f , core cross sectional area A , core relative permeability μ_r , and the square of the total number of turns, i.e., $(N_p)^2$. At a high frequency f_h , where the total electrical length of the balun winding is approximately one half wavelength, the impedance Z_M of the balun winding is resistive with a magnitude determined by the transformer losses. At still higher frequencies the impedance Z_M of the balun winding is capacitive and its magnitude decreases to a small value at the frequency f_f , when the electrical length of the winding is approximately a full wavelength. The magnitude of the capacitive reactance at a frequency f , somewhat less than f_f is proportional to $(f_f - f)$ and inversely proportional to the diameter of the balun winding. Therefore, the maximum bandwidth of operation for a low power balun is achieved by using a high permeability core (high μ_r) with a small cross sectional area A , wound with a large number of turns N_p of a small diameter coaxial line.

Several other factors must be taken into consideration in the design of a high power balun in addition to those set forth above. These relate to the maximum flux density in the high permeability magnetic core, the dielectric strength of the winding insulation, and the

necessity for removing heat from the transformer core and windings. All high permeability magnetic cores have a maximum allowable flux density B_m determined by the permissible non-linearities of the magnetic core

material which increase in direct proportion to flux density B . In a balun the flux density B in the core is proportional to $V_u f N_p A$, illustrating that in a given balun, maximum core flux density always occurs at the lowest operating frequency.

In the design of a high power balun V_u , is a known function of operating power level, and the lowest operating frequency f_l is specified. These parameters set the requirement on the product $N_p A$ which must be made large enough to keep B below its upper limit at the lowest operating frequency. It is often found necessary to use large diameter, low resistance conductors, particularly for the balun winding, and to immerse the balun in high dielectric strength oil to provide the required insulation resistance between the windings and to transfer heat away from the windings and core. The permitivity of the oil reduces the frequency f_f at which the balun winding is a full wavelength long and the large diameter of the winding reduces Z_M at frequencies slightly below f_f . However, the oil and winding conductor diameter have no appreciable effect on Z_M at low frequencies.

The usual result of these considerations is that a high power balun has a core of large cross sectional area A , few turns N_p and great winding length, so that in comparison to a low power balun the low frequency limit of operation is raised and the high frequency limit of operation lowered, resulting in reduced overall bandwidth.

Attention is now directed to FIG. 3 which is a diagram of a novel balun in accordance with the present invention, capable of providing a balanced impedance Z_B , which is greater than the unbalance impedance Z_U . In FIG. 3, elements or parts, similar to those in the foregoing described figures, are designated by like numerals. This balun, in addition to the balun winding 11, includes a balanced impedance transforming winding 30, consisting of wire segments 31 and 32, which connects the balanced terminals 25 and 26 to the outer conductor 14 across the gap 18. As shown in FIG. 3, the balanced impedance transforming winding 30 comprises a wire 31 which is wound about the left side of the core, interconnecting terminal 26 to the outer conductor 14 which is on the right side of the gap. Winding 30 also includes a wire 32 which is wound about the right side of the core, interconnecting terminal 25 to the outer conductor 14 which is on the left side of the gap.

As long as the electrical length of winding 30 is small with respect to a wavelength, the balanced impedance Z_B across terminals 25 and 26 is related to the balanced impedance Z_G across the gap, and therefore to the unbalanced impedance Z_U which equals Z_G , by the relationship

$$Z_B = Z_U (N_s/N_p)^2 \quad (4)$$

In the particular example $N_p=6$ since the number of turns from the gap to ground is 3. $N_s=18$, since the total number of turns from each balanced terminal to ground consists of six turns of the balanced impedance transforming winding 30 and three turns of the balun winding 11 for a total of nine. Thus,

$$Z_B = (18/6)^2 Z_U = 9 Z_U \quad (5)$$

Since both the balun winding 11 and the impedance transforming winding 30 are wound symmetrically with respect to ground, the balanced terminals are electrically balanced with respect to ground at all frequencies. The low frequency limit of operation of this type balun is determined both by the impedance considerations and the power considerations herebefore discussed for the balun shown in FIG. 1. The impedance match of this balun at high frequencies is also influenced by the decrease in the impedance Z_M of the balun winding at the high frequencies as is the case with the aforesubscribed balun. However, an additional consideration applies to the particular balun of FIG. 3 due to the incorporation of the balanced impedance transforming winding 30.

This winding and the outer shield 14 of the balun winding 11 form, in effect, a two conductor transmission line. When the length of this line is an appreciable fraction of a wavelength, in order to achieve reflectionless transmission along it, it is necessary to adjust the characteristic impedance Z_0 of this line so that it is related to the impedance level along the balanced impedance transforming winding which varies from $Z_G = Z_U$ at the gap to Z_B , which in the example equals $9 Z_U$, at the balanced terminals 25 and 26.

As is appreciated, the characteristic impedance of a two-conductor transmission line is a function of the logarithm of the ratio of the distance between the two conductors and their diameters. In the present invention their diameters are not changed. However, the distance between them is varied by increasing the spacings between the turns of the balun winding and the turns of the balanced impedance transforming winding 30 from the gap 18 toward the balanced terminals 25 and 26.

For operation at frequencies where the electrical length of the balanced impedance transforming winding is less than approximately one-third wavelength it is sufficient to make the average characteristic impedance of the equivalent transmission line equal to $(Z_B \times Z_U)^{1/2}/2$. For operation at higher frequencies it is necessary to continuously vary the characteristic impedance Z_0 , from a value of $Z_U/2$ at the gap region along the length of the winding to a value $Z_B/2$ at the balanced terminals. This is achieved by controlling the spacings between the turns of the balun winding 11 and the adjacent turns of the balanced impedance transforming winding 30. This aspect of the invention may be further explained in conjunction with FIG. 4. Therein, the two-conductor transmission line formed by the outer shield 14 of the balun winding 11 and the impedance transforming winding 30 is represented by conductors 11a and 30a. To vary the characteristic impedance of this line the spacing between the two conductors increases from one end 33 to the other end of the line 34. The insulating boards 20 and 21, shown in FIG. 2 are particularly useful for controlling the spacings between the turns of the windings. This is achieved by providing properly spaced holes 22 in each board and winding the two windings therethrough.

The length of the balanced impedance transforming winding 30 increases in terms of a wavelength at higher frequencies. Also, its length becomes significant when a large magnetic core is employed for high power

operation. However, by controlling the spacings between the turns of the two windings, the effect of the length of the balanced impedance transforming winding is greatly reduced, thereby enabling the novel balun to operate at high frequency and at high power levels.

In FIG. 3, each of the wires of the balanced impedance transforming winding 30 is shown wound on a different half of the core 12. If desired, each wire can have some turns on each core half. This may be advantageous to minimize the voltage difference between adjacent turns of the balun and the balanced impedance transforming windings, thereby minimizing the dielectric stress on the winding insulation. Such a winding arrangement may also be advantageous in achieving the required variation in characteristic impedance Z_0 of balanced impedance transforming windings.

Such an arrangement is shown in FIG. 5 which is a diagram of a high power balun with a balanced impedance Z_B which is equal to $49/4 Z_U$. In this particular balun both the gap 18 and the balanced impedance transforming winding 30 occur on opposite sides of the high permeability magnetic core 12. Voltage differences between adjacent turns of the two windings throughout the balun are minimized. Consequently, dielectric stress on the winding insulation and on the core is minimized. The embodiment of FIG. 5 is preferred where the high power limit of the balun is controlled by the allowable dielectric stresses.

Although herebefore each of the baluns has been described with a balun winding consisting of a coaxial transmission line, the invention is not limited thereto. If desired, the balun winding may include one half winding consisting of an unbalanced three-wire transmission line, in which the center wire forms the center conductor of the transmission line and the two outer wires, which operate in parallel the outer conductor of the line. The other half of the balun winding consists of a single conductor. Such an arrangement is shown in FIG. 6. Therein the balun winding is designated generally by numeral 40, and the three-wire transmission line is designated by numeral 41. Numeral 42 designates the center wire, and the two outer wires are designated by numerals 43 and 44. The transmission line 41 is wound about the core 12 from the unbalanced end, at which the center wire 42 is connected to the unbalanced terminal 15 and the wires 43 and 44 are grounded. At the gap 45 the ends of the two outer wires are tied together by a wire section 45a and to the balanced terminal 25, as shown in FIG. 7. The latter is a side view of the balun of FIG. 6 and is useful in highlighting the connections at the balanced end 45.

The center wire 42 is connected to the single conductor 46 which forms the other half of the balun winding and to the other balanced terminal 26. The single conductor 46 is wound about the other half of the core and its other end is grounded. Conductor 46 has a self-inductance per unit length which is equal to the self-inductance per unit length of the two outer conductors 43 and 44.

The balun with the three-wire transmission line winding has the advantage over the balun with the coaxial line winding in that higher values of balun winding characteristic impedance Z_U can be achieved, while maintaining a large diameter for the center conductor.

It should be appreciated that the balun shown in FIG. 6 is of the non-impedance transforming type. That is, therein $Z_B = Z_U$. Clearly, if desired it can be operated to provide a balanced impedance Z_B which is smaller than Z_U by connecting one balanced terminal to conductor 46 and the other to 43 and 44, in a manner similar to that shown in FIG. 1. Also, it may be operated to provide a Z_B greater than Z_U by incorporating balanced impedance transforming windings as shown in FIGS. 3 and 5.

There have accordingly been shown and described herein several embodiments of baluns, capable of high power and/or wideband operation of the non-impedance and primarily of the impedance transforming type. Common to all baluns is the use in each of a single core on which the balun winding is wound. At a gap region of the balun winding a balanced impedance Z_B is present which equals the unbalanced impedance Z_U . In most of the embodiments of the present invention the balanced terminals are connected to the balun winding at points other than at the gap region to provide a balanced impedance Z_B which is smaller than the unbalanced impedance (see FIG. 1) or to the gap through an impedance transforming windings (see FIGS. 3 and 5). For high frequency operation and/or for high power applications, the spacings between the balun and impedance transforming windings are controlled to minimize the effect of the length of the impedance transforming winding, in terms of wavelength at the higher frequencies, or due to the use of a large magnetic core. To minimize dielectric stresses and magnetic core losses, as well as to control the spacings between the windings, two apertured insulating cards, placed on opposite sides of the core, are used (see FIG. 2), with the various windings being wound through appropriately spaced holes in the cards. The description includes embodiments in which a coaxial transmission line or a three-wire transmission line is used for the balun winding.

Although particular embodiments of the invention have been described and illustrated herein, it is recognized that modifications and variations may readily occur to those skilled in the art and consequently it is intended that the claims be interpreted to cover such modifications and equivalents.

What is claimed is:

1. A balun transformer comprising:
a single high permeability magnetic core;
unbalanced terminal means;
balun winding means wound about said core, said balun winding means comprising first winding means wound about one portion of said core from said unbalanced terminal means to a gap region and second winding means wound about another portion of said core from said gap region to said unbalanced terminal means, whereby a balanced impedance is present across said gap region which is substantially equal to an unbalanced impedance, definable as Z_U , across said unbalanced terminal means;
first and second terminals; and
impedance transforming means for connecting said first and second winding means to said first and second terminals respectively, to provide a balanced impedance, definable as Z_B , across said

first and second terminals, Z_B being not equal to said unbalanced impedance, with the number of turns of said balun winding means between said gap region and said unbalanced terminal means being $N_p/2$ and the number of turns about said cores between each of said first and second terminals and said unbalanced terminal means being $N_s/2$ where $N_s \neq N_p$, whereby

$$Z_B = (N_s/N_p)^2 Z_U$$

2. A balun transformer as described in claim 1 wherein said impedance transforming means comprise first and second conductors which are not wound on said core, said first conductor being connected between said first terminal and said first winding means at a point which is a prescribed number of turns from said unbalanced terminal means and said second conductor is connected between said second terminal and said second winding means at a point which is at said prescribed number of turns from said unbalanced terminal means, whereby $N_s < N_p$ and $Z_B < Z_U$.

3. A balun transformer as described in claim 1 further including first and second insulating means on opposite sides of said core, said insulating means defining winding-spacing apertures, with said balun winding means being wound about said core, through said apertures, so that the spacings of the windings from said core and the spacings between winding turns are controlled by the apertures through which the winding turns are wound.

4. A balun transformer as described in claim 1 wherein the number of turns of said balun winding means between said gap region and said unbalanced terminal means, defined as $N_p/2$ is greater than the number of turns about said core between each of said first and second terminals and said unbalanced terminal means defined as $N_s/2$, whereby $Z_B < Z_U$.

5. A balun transformer as described in claim 1 wherein said impedance transforming means comprise impedance transforming windings, extending from said first and second balanced terminals coupled to said first and second windings and wound about said core whereby $Z_B > Z_U$.

6. A balun transformer as described in claim 5 wherein said impedance transforming means comprise a first impedance transforming winding connected between said first balanced terminal and said first winding means and wound about said core whereby the total number of turns between said first balanced terminal and said unbalanced terminal means is definable as $N_s/2$, and a second impedance transforming winding connected between said second balanced terminal and said second winding means are wound about said cores so that the total number of turns between said second balanced terminal and said unbalanced terminal means is $N_s/2$, whereby $N_s > N_p$ and $Z_B > Z_U$.

7. A balun transformer as described in claim 6 further including first and second insulating means on opposite sides of said core, said insulating means defining winding spacing apertures, with said balun winding means and said impedance transforming windings being wound about said core through said apertures, which control the spacings between the windings and the core and preselected spacings between turns of said balun winding means and said impedance transforming windings.

8. In a balun transformer of the type including a single high permeability magnetic core and balun winding means wound about said core and extending from unbalanced terminal means with an unbalanced impedance, definable as Z_u , to a gap region having a balanced impedance, definable as Z_c , where $Z_c = Z_u$, the improvement comprising:

impedance transforming means coupled to and including at least a portion of said balun winding means and further coupled to first and second balanced terminals for providing a balanced impedance across said first and second balanced terminals, definable as Z_B , which is not equal to Z_u .

9. The arrangement as recited in claim 8 wherein Z_B is a function of the number of wound turns, definable as $N_s/2$, of said impedance transforming means between each of said first and second balanced terminals and said unbalanced terminal means and the number of wound turns, definable as $N_p/2$, of said balun winding means between said gap region and said unbalanced terminal means, whereby

$$Z_B = (N_s/N_p)^2 Z_u.$$

10. The arrangement as recited in claim 9 wherein $N_s/2$ is less than $N_p/2$ with each of said first and second balanced terminals being directly connected to said balun winding means at a point which is an equal number of turns from said unbalanced terminal means.

11. The arrangement as recited in claim 9 wherein

5

10

said impedance transforming means include first and second conductors, each with first and second ends, means connecting said first and second balanced terminals to the first ends of said first and second conductors respectively, means connecting the second ends of said first and second conductors to said balun winding means at points which are an equal number of turns from said unbalanced terminal means, with each of said first and second conductors having at least a portion thereof wound about said core, so that the number of turns between each of said balanced terminals and said unbalanced terminal means is the same, being equal to $N_s/2$, which is greater than $N_p/2$.

12. The arrangement as recited in claim 11 further including winding control means for controlling the spacings between the turns of each of said first and second conductors and the turns of said balun winding means.

13. The arrangement as recited in claim 12 wherein said balun winding means comprises a coaxial cable and said winding control means comprises first and second insulating boards, spaced on opposite sides of said core, and defining spaced apertures through which said coaxial cable and said first and second conductors are wound, whereby the spacings between turns are controlled by the apertures' spacings.
